UNITED STATES PATENT OFFICE.

WALTER W. WOOD, OF DULUTH, MINNESOTA.

ELEVATOR-CAR LOCK.

No. 858,552.

Specification of Letters Patent.

Patented July 2, 1907.

Application filed August 25, 1906. Serial No. 331,984.

To all whom it may concern:

Be it known that I, WALTER W. WOOD, a citizen of the United States, residing at Duluth, in the county of St. Louis and State of Minnesota, have invented certain new and useful Improvements in Elevator-Car Locks; and I do hereby declare the following to be a full, clear, and exact description of the invention, such as will enable others skilled in the art to which it appertains to make and use the same.

10 My invention relates to locks for elevator cars, and has for its object the provision of a convenient and safe means engaging the operating hand cable of an elevator so as to prevent movement of the elevator car or the said cable by persons at a different floor than that at 15 which the elevator car is so stopped.

It consists of the constructions, combinations and arrangements of parts hereinafter described and claimed.

In the drawings, Figure 1, is a side elevation of my said invention. Fig. 2, is a plan view of a modified 20 form thereof. Fig. 3, is a horizontal sectional view of said invention on the line A—B of Fig. 1 showing also the cable in broken lines, in locked position.

In the drawings 1 is a portion of an elevator car; 2 is a hand cable for operating the elevator, 3 and 4 are collars spaced a short distance apart and secured to said cable and stationary with respect thereto. Secured to said elevator car in any suitable manner, as, for example, preferably, by the standard 1^a erected upon and secured to the floor of said car, and the screw or bolt 1^b is a bracket 25 comprising the parallel or nearly parallel arms 6 and 7 and the enlarged loop portion 8. Extending from one of said arms as for example the arm 7 is the supplementary bracket 9, upon which is supported a bolt 10 beveled at its forward end as at 10^a and adapted in operative position, to extend across, or nearly across the space 30 between said arms and in retracted position to recede upon said bracket 9 to clear or approximately clear said space. Said supplementary bracket is preferably cylindrical. Behind said bolt is positioned an extension 35 spring 11 adapted to bear against a suitable relatively fixed abutment as, for example, the screw cap 12 and to bear at its opposite end against said bolt to force said bolt across the space between said bars. Pivotally secured in any suitable manner to one of said arms, as, 40 for example, the arm 7, is a lever 13, which is adapted at one end to engage said bolt to retract it in opposition to said spring, and extending from said lever is a handle portion of any suitable form, as the handle 13^a. Said cable extends through said loop 8, which is of sufficient 45 diameter to permit of the free passage through it of said cable and collars, but the arms 6 and 7 are only spaced

sufficiently far apart to permit of the passage of the cable between them and are a bar to the passage between them of said collars. Similar pairs of said collars are preferably located on said cable opposite or near 55 the several floors of the building within which the elevator or car is operated, and in such position with relation to said bracket and floors as that when said arms extend on either side of the cable and between the members of any pair of said collars said elevator car will 60 be in discharging or receiving position at one of the floors of said building.

In Fig. 2, is shown a modified form of said invention, in which the standard 1^a is omitted and the bracket comprising the arms 6 and 7 is secured to the side wall of 65 the elevator. The lever 13 is also omitted and a pin 10^b is provided for retracting the bolt, which pin extends into said bolt through a slot 9^a formed in said bracket 9.

In operation, when it is desired to lock said operating cable so that it can not be pulled to open a valve or so 70 that it can not be pulled to hoist the elevator (according to the use to which said cable may be put), the operator sways said cable out of the vertical line and against the beveled edge of said bolt, causing it to wedge back said bolt and to pass beyond the same into space between 75 the arms 6 and 7 said operator taking care to sway against said bolt the portion of the cable which extends between the members of a pair of said collars, so that one of said collars will closely approach said arms above the same and the other of said collars will closely approach said arms below the same. After the passage 80 thereby of said cable, said bolt is shot forward by said spring to prevent the escape of said cable into said loop, and any material upward or downward movement of either the cable or the car will be prevented by said 85 arms and collars. To release said cable into said loop, the lever 13 is operated to retract said bolt, whereupon the cable springs out into the loop, or may be drawn out into the same, and may then be operated as a valve-controlling cable or as a hoisting cable, as the case may be. 90

What I claim is;

1. In an elevator car lock, the combination with the elevator car and operating hand cable, of a bracket comprising two approximately parallel arms and one enlarged loop portion secured to said elevator car, a bolt extending in operative position across the space between said arms, yielding means for holding said bolt in operative position and adapted to permit the retraction of said bolt, means for retracting said bolt, said loop portion being positioned so as to partly encircle said cable when the cable is in 95 normal position for operation, a pair of collars secured to said cable and spaced a short distance apart and adapted to pass through said loop portion when said cable is in operative position, said collars being adapted respectively 100

- to bear against the upper and lower edges of said arms when said cable is swayed out of normal position so as to move past said bolt and into the space between said arms, that portion of the cable which is between said collars.
- 5 2. In an elevator car lock, the combination with an elevator car and operating hand cable therefor of two arms secured to said car and adapted to extend on opposite sides of said cable when said cable is swayed between them from its normal position, a bolt extending in operative position across the space between said arms, a pair of collars secured to said cable and spaced a short distance

apart and adapted respectively when the part of said cable between said collars is swayed out of normal position and past the bolt and into the space between said arms, to extend transversely across said arms.

15

In testimony whereof I hereunto affix my signature in presence of two witnesses.

WALTER W. WOOD.
